(57) **CLAIM**

The ornamental design for a bottle carrier, as shown and described.

DESCRIPTION

FIG. 1 is a top, front, right perspective view of a bottle carrier showing our new design.

FIG. 2 is a bottom, rear, left perspective view thereof.

FIG. 3 is front view thereof.

FIG. 4 is a rear view thereof.

FIG. 5 is a top view thereof.

FIG. 6 is a bottom view thereof.

FIG. 7 is a right view thereof; and,

FIG. 8 is a left view thereof.

The broken lines of equal length in the drawings depict portions of the bottle carrier that form no part of the claimed design. The stipple shading represents a contrast in appearance.
